APPARATUS FOR SPLITTING WARP SHEETS
AND THE LIKEJohn R. Andrews, Jr., Uxbridge, Mass., assignor
to Bachmann Uxbridge Worsted Co., Inc., Ux-
bridge, Mass., a corporation of Massachusetts

Application October 20, 1949, Serial No. 122,483

5 Claims. (Cl. 28—40)

1

This invention relates to an apparatus for splitting a warp sheet into a plurality of sheets.

The splitting of a warp sheet, as for example after sizing and in advance of the drying step, has customarily been performed using one or more splitter rolls which are loosely mounted in supporting brackets so that rotation can be imparted to the rolls by the frictional drag of the warp sheet. Under these conditions the rate of rotation of a splitter roll is not constant nor is the most desirable speed obtained to avoid accumulation of the size on the splitter roll which condition is undesirable since from time to time comparatively large masses of the size are detached and deposited onto the warp sheet.

It is an object of this invention to improve the present day splitter roll apparatus and to provide simple, practical and durable apparatus of this kind.

Another object of the invention is to provide a splitter roll assembly which is readily transferable and movable as a unit.

Another object of the invention is to provide apparatus whereby a splitter roll may be readily mounted and demounted, and wherein positive means are provided for driving a splitter roll at a predetermined rate of speed.

Another object of the invention is to provide a plurality of splitter rolls which may be driven in unison at uniform speed which is not necessarily the same surface speed as the speed of travel of the warp sheet.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which:

Figure 1 is a front elevational view of a splitter roll assembly including mounting means and drive means;

Figure 2 is an end view looking in the direction of the arrow shown at the right in Figure 1;

Figure 3 is a vertical sectional view taken on the line 3—3 of Figure 2; and

Figure 4 is a detailed view showing one end of one of the splitter roll spindles.

In the preferred form of the invention dis-

2

closed herein I provide the brackets 10 and 12 projecting forwardly from support members 14 and 16 and shown herein as being attached thereto by screws.

Brackets 10 and 12 as shown herein comprise spaced arms 10^a, 10^b, and 12^a, 12^b respectively, the arms of each bracket being desirably connected in front by the cross webs or members 10^c and 12^c. Each of the arms of each bracket is provided with apertures 18 and 20, similarly placed and therefore aligned. Adjacent aperture 18 a slot 22 is provided in each of the arms of each bracket and adjacent aperture 20 slot 24 is provided in each of the arms of each bracket to receive bolts for adjustably positioning the blocks b through which the spindles extend and are received in ball bearing mounts. A single spindle member 26 is mounted to extend through the aligned aperture 18 of the arms of each of the brackets 10 and 12 respectively, and two spindles 26 are shown mounted one above the other in the aligned apertures 20 of the arms of each bracket. Each spindle projects through blocks b provided on the inside and the outside of each arm of said brackets 10 and 12 respectively, each block being slotted longitudinally and held against the bracket arm by means of nut-bolt combinations the blocks for mounting the spindle in apertures 18 being mounted on bolts extending through slot 22, and the blocks for mounting the two spindles in aperture 20 being mounted on bolts extending through slot 24.

Splitter rods 30 are mounted between aligned spindles carried by the opposed brackets as has been described. Thus one splitter rod is mounted between the spindles in apertures 18, and two pairs of splitter rods 30 are provided within the apertures 20 in the arms of brackets 10 and 12 respectively. As shown herein the splitter rods 30 are readily interchangeable as are the spindles 26. At least one end, and as shown herein, preferably both ends of a splitter bar are tapered and flattened and adapted to be received in a V-shaped aperture 26^a provided at the inner end of each of the spindle members 26. Also mounted on each spindle member is a collar 26^b which is slideable forwardly against the shoulder 26^c to prevent accidental displacement and disengagement of an end of a splitter roll from a spindle aperture 26^a, and a spring clip 26^d may be provided to retain the collar 26^b in position.

The spindles 26 are mounted in ball bearings 36 carried by the blocks b and each spindle is thus freely rotatable. On one end of each spindle, beyond the mounting bracket, a sprocket S

is provided by which power from any suitable source may be transmitted to the spindle as for example by a chain 38, see Figure 2, which as shown herein passes over the sprockets S on the spindle ends outside of bracket 12, and over the idler 40, and is positively driven from sprocket 42 on jack shaft 44 which in turn is positively rotated by the chain 46 from any suitable source of power. Thus the speed of rotation which may be imparted to the splitter rods is entirely independent of the speed of travel of the warp sheet which may be divided first by the single rotating splitter rod positioned between the brackets 10 and 12 adjacent their free ends, and each resulting sheet being split again by one of the rotating splitter rods mounted between the brackets 10 and 12 adjacent their ends attached to support members 14 and 16 respectively.

The apparatus described herein has the advantage of being readily assembled to a drying box, such for example as the kind disclosed in co-pending application of Paul R. Rose, Serial No. 25,565, filed May 7, 1948, Patent No. 2,541,383, now Reissue No. 23,535, and is readily transferable as a unit to another drying box.

It will thus be seen that there has been provided by this invention an apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

What I claim is:

1. Apparatus for splitting a warp sheet into a plurality of sheets comprising a rod, rotatable spindles for receiving the ends of said rod, and means for rotating said spindles one of said spindles having a slot extending across its face diametrically to permit insertion of a rod end through the side of the spindle, and means for locking said rod end in said spindle.

2. Apparatus for splitting a warp sheet into a plurality of sheets comprising, a rod with flattened ends, rotatable mounting means for receiving the ends of said rod, at least one of said mounting means comprising a spindle having a V-shaped recess at one end to receive one end of said rod, a slideable collar on said spindle movable over said recess to prevent accidental dislodgement of a rod end from said recess, and means for retaining said collar in place, said spindle having means thereon adapted to be driven by a suitable source of power to positively rotate said spindle.

3. Apparatus for splitting a warp sheet into a plurality of sheets comprising a plurality of pairs of bearings, a plurality of splitter rods interchangeably supportable by said pairs of bearings respectively, at least one bearing of each pair being rotatable, at least one end of said rods being

non-circular in cross section, and the said rotatable bearing of each pair having a recess of non-circular cross section to receive the said non-circular end of said rods, adjustable mounting means for one or more of said pairs of bearings whereby the distance between said pairs of bearings respectively is adjustable, and means for rotating the said rotatable bearings in timed relation.

10 4. Apparatus for splitting a warp sheet into a number of sheets comprising three pairs of spindles, the spindles of each pair being positioned in opposed relation, with two of said pairs being disposed in adjacent vertical planes and the 15 other pair being disposed in a vertical plane spaced a substantial distance horizontally from said pairs of spindles, a number of splitter rods each mountable between the spindles comprising any one of said three pairs of spindles and thus 20 being interchangeable between said pairs of spindles, at least one spindle of each pair being rotatable, means for rotating said rotatable spindles in timed relation, and adjustable mounting means for one or more of said pairs of spindles whereby 25 the distance between said pairs of spindles respectively is adjustable.

5. Apparatus for splitting a warp sheet into a number of sheets comprising three pairs of spindles, the spindles of each pair being positioned in 30 opposed relation, with two of said pairs being disposed in adjacent vertical planes and the other pair being disposed in a vertical plane spaced a substantial distance horizontally from said pairs of spindles, a number of splitter rods each mountable between the spindles comprising any one of 35 said three pairs of spindles and thus being interchangeable between said pairs of spindles, at least one spindle of each pair being rotatable, means for rotating said rotatable spindles in timed relation, said rods each being provided with at least one tapered end and said spindles having at least one tapered recess to receive said tapered end thereby preventing relative rotation between a rod and a pair of spindles supporting said rod while providing a loose engagement between said rod and said pair of spindles, and permitting said rod to be readily mounted in or be dismounted from said spindles.
